UNITED STATES PATENT OFFICE.

WALLACE J. HIGGS, OF LEHI, UTAH.

HANDLE-FASTENER.

1,033,171.

Specification of Letters Patent. Patented July 23, 1912.

Application filed March 1, 1911. Serial No. 611,589.

To all whom it may concern:

Be it known that I, WALLACE J. HIGGS, a citizen of the United States, residing at Lehi, in the county of Utah and State of 5 Utah, have invented a new and useful Handle-Fastener, of which the following is a specification.

This invention relates to implements embodying a tool and a helve or handle, such 10 as picks, axes, hammers, and the like, and this invention has for its object to provide a helve adapted to clamp the tool on the outer end thereof between a pair of flanges and at the same time distend that portion of the 15 helve fitting through the socket or hole of the tool, thereby locking the tool against longitudinal, transverse and revoluble motion, the locking means being controlled from the inner end of the helve.

20 To the above ends, this invention is embodied in the novel construction and combination of parts hereinafter described and claimed, reference being had to the accompanying drawings wherein similar reference 25 characters indicate similar parts, and wherein—

Figure 1 is a side elevation of this device, parts broken away. Fig. 2 is a central longitudinal section thereof, with the tool removed. Fig. 3 is a perspective view of the helve or handle, parts broken away. Fig. 4 is a perspective view of a modified wedge and the rod connected thereto, showing the nut disengaged from the end of the rod.

35 Referring in detail to the drawings, the letter T designates the tool proper, in this case the same being illustrated as a pick, having the usual tapering hole or socket therethrough of elliptical cross section, the 40 hole or socket tapering from the inner side outward, or having the smaller end disposed inwardly.

The helve or handle is designated by the letter H, the same being tubular and having 45 the ends thereof closed with the outer end thereof having an elliptical cross section merging into the intermediate tubular portion. The helve or handle H has an exterior flange 5 at the outer end thereof and is provided with spaced pliable actuate wings 6 beyond the said flange. These wings 6 are passed through the hole of the tool from the smaller end to the larger end thereof, and are adapted to readily pass through the 55 smaller end of the tool. A wedge 8 of elliptical cross section fits between the wings 6

and has an external flange 15 projecting from the outer end thereof. A rod 9 is passed longitudinally through the handle or helve H and also passes through the wedge 60 8, the said rod having a square or non-circular head 19 on the outer end thereof fitting into a socket in the outer end of the wedge 8 of corresponding contour. The helve H is provided at its inner end with the 65 annular rabbet 13 and a nut 11 is screw-threaded upon the inner end of the rod 9 and has an annular flange 12 projecting from the inner end thereof and fitting into the annular rabbet 13. The helve or handle 70 is constructed of suitable metal to give the wings 6 a proper resiliency and to give the tubular portion of the handle a proper rigidity.

In use, by tightening the nut 11 the rod 9 75 is drawn inwardly, thereby drawing the wedge 8 between the wings 6 to spread the said wings within the hole of the tool to distend that portion of the helve fitting through the tool, and at the same time the tool is 80 clamped between the flanges 5 and 15. In this manner the tool is firmly held upon the outer end of the helve against longitudinal, lateral or revoluble motion, and the tool is not likely to become loosened as the same is 85 used. By unscrewing the nut 10 and removing same from the inner end of the rod, the rod 9 may be withdrawn from the handle together with the wedge 8, whereupon the tool may be removed from the 90 wings 6. In this manner the tool may be readily attached and detached from the helve, and the helve may be utilized for various tools. By the provision of the means for distending that portion of the helve 95 passing through the tool and for clamping the tool between the flanges a substantial structure is provided.

The wedge as shown in Fig. 4 is not provided with the flange 15, this form of wedge 100 being adapted particularly for use in connection with tools not requiring hard usage.

Having described the invention, what is claimed as new is:

In a device of the character described, the 105 combination of a tool having an elongated tapered hole therethrough, a handle having an exterior flange at its outer end and spaced pliable wings beyond the said flange passing through the hole in the tool from the smaller 110 end to the larger end, a wedge fitting between the said wings and having an outer

flange, a rod connected to the said wedge and passing through the handle to the inner end thereof, and a nut screw-threaded on the inner end of the rod and bearing against the 5 inner end of the handle to distend the said wings and to clamp the tool between the said flanges.

In testimony that I claim the foregoing as my own, I have hereto affixed my signature in the presence of two witnesses.

WALLACE J. HIGGS.
